PROCESS AND MECHANISM FOR SEPARATING INTERMIXED DIVIDED MATERIALS

Kenneth Davis, Ebensburg, Pa., assignor, by mesne assignments, to Peale-Davis Company, Wilmington, Del., a corporation of Delaware

Application July 10, 1922, Serial No. 574,034
Renewed August 23, 1934

24 Claims. (Cl. 209—467)

The invention relates to a novel process and mechanism for separating intermixed divided materials and in certain aspects thereof more especially to such mechanisms particularly adapted to separating intermixed coal and rock and like materials.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part thereof, illustrate one embodiment of the invention, and together with the description, serve to explain the principles of the invention.

Of the drawings:—

Fig. 1 is a vertical longitudinal section taken substantially on the line 1—1 of Fig. 2;

Fig. 2 is a transverse vertical section taken substantially on the line 2—2 of Fig. 3;

Fig. 3 is a full top plan of the mechanism shown in Figs. 1 and 2;

Fig. 4 is a top plan, greatly diminished, showing a somewhat different form from Fig. 3;

Fig. 5 is a diminished horizontal section taken substantially on the line 5—5 of Fig. 2;

Fig. 6 is a diagrammatic view of a battery of the separating units with common vibrating means;

Fig. 7 is a transverse vertical section through a single separating unit and its mounting;

Fig. 8 is an elevation, with parts omitted, showing a different form of vibrating means from that of the preceding figures.

Fig. 9 is the same as Fig. 8 but shows a different longitudinal inclination of the frame; and

Fig. 10 is a diagrammatic plan view of an air-pervious unit showing a modified arrangement of separating partitions.

The invention, especially in the present preferred embodiment, exemplarily illustrated in the accompanying drawings, is particularly capacitated for rapidly, easily and efficaciously separating intermixed divided materials, and is designed especially for such service with intermixed divided materials the fragments or particles of which vary in size through a relatively very wide range of sizes, and in different physical states or conditions.

So far as concerns the feature of successfully and efficiently handling a wide range of sizes, and having especially in mind the separation of intermixed coal and rock, or coal, "bone" and rock, the machine of the present invention effects a substantially complete or perfect separation through the wide range of sizes referred to, thereby obviating the usual troublesome, expensive and time-consuming preliminary close "sizing". This sizing is necessary with the separators now in use, so as to supply the separating machine with the intermixed materials of uniform size within a very small or close range, most separators requiring preliminary sizing within a range of one-sixteenth of an inch. Under practical conditions the machine of the present invention will operate efficiently and will produce substantially perfect results within size ranges varying by one-inch, and usually by nearly two inches. Also, the machine may be variably positioned and otherwise regulated to meet different physical conditions of the material, as later described.

The term "divided" as used herein signifies materials in relatively small parts or particles as differentiated from materials in relatively large parts or masses, and such materials may be broken, granular, pulverulent or otherwise.

In its main features as exemplarily embodied, the invention comprises a relatively wide, long and shallow body or unit in which a corresponding bed of the intermixed divided materials are stratified and thereby separated and delivered at different places or points. The separation and separate delivery are effected by the combined action of upwardly directed air currents, vibration or other movement of the unit, together with a regulable positioning, or variation in the inclination, both transverse and longitudinal, of the unit to secure the best results with the particular intermixed material being operated upon.

The invention comprises means for regulating the longitudinal inclination of the unit, and also independently operating means for regulating the transverse level or inclination thereof without disturbing the vibrating means. It also comprises means or devices for assisting in the separating of the intermixed materials, and for repeating or continuing the separating action on any parts or sizes of the intermixed materials which are not separated by the first stratifying action, these various instrumentalities being regulable for the most efficient cooperation in separating intermixed materials of different kinds or in different physical conditions.

Other features of the invention will be set forth

primarily in connection with the following detailed description of the invention, and it will be understood that the foregoing general description and the following detailed description are both explanatory and exemplary of the invention, but are not restrictive thereof.

Referring now in detail to the present preferred embodiment of the invention, illustrated by way of example in the accompanying drawings, the separating units are shown in Figs. 1 to 4 mounted in pairs with respect to the vibrating means, but being independently adjustable side-wise or transversely with respect to each other.

The respective separator units as so mounted each comprise a body having an air-pervious bottom 1, of suitable material or structure, and preferably constituted of wire mesh. These units comprise a frame having side reaches 2 and 3 and end reaches 4 and 5, the wire mesh or other air-pervious bottom 1 being fixed to a rectangular frame 6 fitting within the general frame just described and supported therewithin by means of brackets 7.

The end at which the intermixed materials are supplied to the unit may be conveniently styled the rear end, and the supplying means may be of any proper or suitable form for uniformly supplying the intermixed materials at the rate at which they are separated by the mechanism.

As embodied, each unit is provided at its rear end with a hopper 12, having its two side walls and its rear wall preferably of air-pervious material, such as the wire mesh. As shown, the hopper has an inwardly and downwardly inclined rear wall 13, and inwardly and downwardly inclined side walls 14 and 15, the inclination of the various walls varying as shown in the illustrated embodiment. Preferably, the hopper walls from a point somewhat above the bottom incline 40 downwardly and outwardly to prevent choking and jamming of the materials as they feed down.

The front wall 16 of the hopper is shown solid in Figs. 1, 2 and 3, and provides a mounting for a feed-regulating slide, later described. The hopper is mounted upon the separating unit in a suitable manner as by brackets 17 fixed to the hopper and to the frame of the unit.

In accordance with one feature of the invention, the air pressure is utilized for cleaning the dust out of the intermixed divided materials preparatory to the separating action, the air-pervious walls of the hopper being desirable for this purpose. In connection therewith, means are provided for permitting a desired or regulated amount of the air current to pass upwardly through the hopper, just sufficient to effect this cleaning action.

In the embodied form thereof, a slide 24 works in an aperture in the end 4 of the frame of the unit, the slide moving on the top surface of the bottom 1 of the units. This slide is supported on a bracket or brackets 26, fixed to the exterior of the frame piece 4 and extending outwardly therefrom. Means for holding the slide 24 in the desired position so as to admit the proper amount of air current into the hopper are provided. For this purpose, as shown in Fig. 1, the slide 24 is slotted, a bolt 27 passing through the slot and through the bracket 26. Thus by moving the slide in and out, the amount of air passing upward through the hopper can be accurately regulated.

Referring now to the means for regulating the flow or supply of intermixed materials to the body of the unit, a vertically movable slide 28 is

mounted on the external face of the hopper wall 16, by means of a bolt and slot mounting 29. The slide 28 is moved up and down to regulate the size of the throat or port 30, through which the intermixed materials pass from the hopper forwardly into the body of the unit to be subjected to the stratifying and separating agencies and action.

Referring now to the embodied form of means for transversely inclining or positioning the separating unit, devices are provided for varying the inclination transversely of the unit and in connection therewith is a flexible air-tight connection between the unit and the chamber which supplies the air under pressure beneath the floor or table 1, whereby the upwardly-directed air currents are created. As embodied, the air chamber is mounted on a vibratable frame, which in turn is mounted upon a non-vibratable, but regulably longitudinally inclinable frame or support, all of which is later described in detail.

The upper part of the air chamber 35 has preferably rectangular walls, comprising end walls 36 and 37 and side walls 38 and 39. The lower part of the air chamber has inwardly and downwardly inclined end walls 40 and 41 and similar side walls 42 and 43, these walls terminating in a supply pipe (not shown) receiving the supply of air under pressure from a blower fan, compressor or any other suitable source. A suitable and convenient form of this mechanism is shown in my copending application Ser. No. 566,639 filed June 7, 1922, now Patent No. 1,786,739.

Having in mind the double mounting of the units constituting one feature of the invention, a plurality of internal frame members are provided having, respectively, bottom cross reaches 46, and vertical side reaches 47 and 48, and upwardly and inwardly inclined top reaches 49 and 50 with a central supporting part 51. These frames are supported within the air chamber by suitable means, and as shown, bolts 52 pass through the frames and through the air chamber walls and into the vibratable frame later to be described. Disposed centrally and longitudinally of the general structure just described, is a supporting beam 55, extending between the end walls 36 and 37 of the air chamber and resting upon and being fastened to the part 51 of the supporting frames by bolts 56.

Further, in this embodied form, the reach 3 of the two unit frames is pivoted or hinged to the beam 55 by suitable means, such as hinges 58. Cooperating therewith on the opposite side of the unit are a plurality of screw-bolts 60, pivoted at 69 to the wall 38 of the air chamber. These bolts pass through a plate or board 61, which extends outwardly from and along the unit frame piece 2, and is provided at its ends with supporting and attaching brackets 62. Nuts 63 and 64 are threaded on the screw bolts 60 on either side of the plate 61, and together with the hinge mounting on the other side, they support the unit and vary its level or transverse inclination.

The flexible air-tight connection between the air chamber and the unit frame consists preferably of a flexible sheet 65, of canvas or any other suitable material having one edge fastened to the top of the air chamber and the other edge fastened to the bottom of the unit frame, as is best shown in Figs. 1, 2 and 7.

If desired, a baffle plate 66, of any desired shape and size, and preferably with air passages 67 of suitable and variable size and location, as desired, may be employed within the air chamber. Such

a plate is shown, supported from and positioned by means of bolts 68 passing through the baffle plate and through the bottom reach 46 of the supporting frames.

5 The vibratable mounting for the unit and the unit vibrating means, as embodied, comprise a frame fixed to and supporting the air chamber, and therewith the separating unit proper. The frame, as embodied, comprises two bars 74 and 10 75, extending longitudinally of and fixed to the exterior of the air chamber side walls 38 and 39, the beams extending beyond the air chamber at each end. Cooperating with this frame, which is fastened to the vibratable structure, as 15 just described, is a non-vibratable supporting frame.

In accordance with certain features of the invention, this non-vibratable supporting frame is provided with means for varying its inclination 20 and therewith the longitudinal inclination of the unit. As embodied, this non-vibratable but inclinable frame comprises side reaches 76 and 77 and end reaches 78 and 79. Fixed to the non-vibratable frame near the corners thereof and projecting upwardly therefrom are pins 80, which pass through holes in the ends of the bars 74 and 75. Helical springs 81 are in compression between the bars 74 and 75 and the supporting vibratable frame. If desired, the pins 80 may be 25 shouldered as shown in Figs. 1 and 2 to constitute a stop for the downward movement of the vibratable frame.

The embodied form of means for supporting and for varying the inclination of the supporting frame comprises a pivot mounting therefor, located preferably at or near the center of the side reaches 76 and 77. As shown, the side reaches 76 and 77, respectively, are rockably supported upon corresponding bolts 84, mounted in 30 pillars or pedestals 85, and having heads 86 and nuts 87 screw-threaded on the bolts. A retaining block or cap 88 is fastened to the under side of the frame pieces to retain the frame in position upon its pivot bearings.

45 The inclination regulating means comprises one or more legs or bars 92, pivotally supported at 93 upon the supporting frame, and having a bolt and slot connection 94 with corresponding pillars or pedestals 95. Thus the longitudinal inclination of the unit may be varied and regulated nicely as desired, while the entire structure is firmly supported upon its pivot bearings.

50 In Fig. 1 the unit is shown inclined downwardly from the rear or feed end to the front or discharge end; in Fig. 8 the unit is level longitudinally; while in Fig. 9 it is shown with a forward and upward longitudinal inclination. The variations in the longitudinal inclination of the unit are effected merely by adjustment of the 55 bolt and slot connections, as already described.

The embodied form of vibrating means is designed to vibrate the double unit, as shown in Figs. 1, 2 and 3. Said embodied form comprises a frame 96, fixed to and projecting upwardly from the top of the beam 55, and having at the top thereof a plate or part 97 having a curved slot 97^a therein. A contact block 97^b is slidable along the part 97 and a bolt 97^c holds it in the desired position for cooperation with the actuating cam 70 for any desired inclination of the separating unit, while it is independent of changes and variations in the transverse positioning or inclination of the separate units. Extending transversely to the unit and above the frame 96 is a shaft 98, 75 having fixed thereon a cam 99, the shaft 98 be-

ing rotated in any suitable manner. The cam 99 is preferably shaped to give a relatively slow depression and a relatively sharp and sudden return upward movement to the separating unit.

5 The operation of the foregoing mechanism will be clear without further extended description. As the cam 99 rotates, it will depress the frame 97, which depresses the beam 55 and therewith the air chamber and both the separating units belonging with it, against the compressed springs 10 81, the springs returning the units and structure after the cam.

In Fig. 6 there is shown diagrammatically a plurality of the double units all operated from a single shaft 98. In this case, the cams 99 are 15 releasable from their shaft, and as shown, they have hubs 100 provided with clamping screws 101, the shaft having a plurality of bearings 102, and at one end thereof a driving pulley 103.

In Fig. 7 a modification is shown wherein only 20 a single separating unit is mounted upon the air chamber, the air chamber in this case being correspondingly of narrower width. The various parts are shown in this figure with the same reference numerals applied thereto with an exponent *a*.

In Fig. 8 is shown a different form of mounting and a different vibratory movement from the separating unit or units, the units themselves being, if desired of the same construction, and likewise the supporting frame. The parts which are unchanged in this figure from the foregoing figures have the same reference numerals applied thereto. The vibratable frame members 74 and 75 are pivoted at 110 and 111, respectively, and are supported by, arms 112 and 113. These arms at their other ends 114 and 115 are pivoted to the inclinable but non-vibratable frame already described.

30 In the embodied actuating means, a shaft 116 is journaled in a plurality of bearing brackets 105, carried upon the inclinable supporting frame, the shaft being driven by any suitable means, such as a belt pulley 117, fixed to the shaft, and over which runs a belt 118. Fixed on shaft 116 45 is a cam 119 shaped, as will be seen from Fig. 8, to give a relatively slow movement in one direction and a sharp return movement in the opposite direction. Located at the opposite end of the frame members or beams 74 and 75 of the vibratable frame are helical compressed springs 120, in compression between the ends of the beams and lug 121 fixed on the inclinable and non-vibratable frame. Two cooperating limiting stops are provided, one stop 122 being fixed 50 on the vibratable structure and the other stop 123 being fixed upon the non-vibratable structure. These stops create a sharp and sudden impact at the end of the movement of the unit.

55 With the shape of the cam as shown and with the inclination of the arms 112 and 113 as shown, the separating unit has a relatively slow backward and downward movement and a relatively quick and sharp upward and forward movement. This movement may be varied relatively 65 in speed and direction as desired, and as found most efficient from experience, especially to meet different kinds and physical states of the intermixed divided materials.

This vibration or movement of this peculiar 70 nature, with a component along the direction of travel of the material being separated, and especially the sharp upward and forward movement terminating in the sharp impact, will be found very efficacious with most materials and 75

under most conditions, especially in increasing the output of a unit while maintaining the desired completeness of separation of the materials.

- 5 Cooperating with the material stratifying and separating devices already described are other devices for assisting in the stratification and separation, but more especially operating to maintain the stratification and separation and to direct the separated material to separate places of discharge.

These devices now referred to are capacitated for use independently of many of the mechanisms already described, and are adapted to enable or to assist, the mechanism in separating successfully and efficiently the intermixed materials, especially when the fragments or particles vary through a wide range of sizes, or where thorough and complete separation of three intermixed materials, such as coal, "bone" and rock must be effected.

Pursuant to this feature of the invention, and as embodied, the separating units have a plurality of side walls, or separating partitions, preferably on the outer side of the units only, when the units are made laterally inclinable. The separating partitions are in contact with and project upwardly from the air pervious bottom 1, and are disposed longitudinally thereof. If desired, these separating partitions may be inclined either inwardly or outwardly along and toward the forward end of the bed or they may be disposed straight therealong. They may be arranged, also, in parallel or non-parallel relation with respect to each other.

In Figs. 1 and 2, three spaced-apart separating partitions 130, 131 and 132 are shown, extending along the units, and converging inwardly toward the forward end of the unit and at the same time diverging somewhat from each other.

In the preferred general arrangement, the port 30 from the hopper discharges onto the air-pervious bottom 1 within the inner separating partition 130, all the intermixed materials thus being primarily subjected to the stratifying and separating action and the impulsion forwardly along the unit within this partition 130. The most of the heavier material is thus immediately separated and restrained, while all the lighter material is immediately separated and is free to move transversely from the unit over the separating partitions. Any tendency to temporary uniform effect of the air current on large fragments or particles of the lighter materials and small fragments or particles of the heavier material is corrected by the action between the separating partitions.

These separating partitions are supported in position by suitable means such as brackets 134, and these brackets may be screw-held and thus be movable whereby their position and relative disposition to the unit, and to each other, may be varied and changed as found desirable with the particular materials being separated. The rear brackets 134 are mounted on outwardly and forwardly inclined, vertically disposed walls 135 mounted on a closed part of the top of the air chamber.

In Fig. 4 is a somewhat diagrammatic plan, showing a plurality of straight separating partitions diverging forwardly and outwardly along the unit. In my co-pending application, Ser. No. 574,033 filed July 10, 1922, now Patent No. 1,787,340 separating partitions are shown, which are of different shapes, are transversely variably posi-

tionable with respect to each other and to the unit, and which are interchangeable with side partitions of different forms or shapes, and these features may also be utilized in the present case and with the features of invention herein set forth.

In Fig. 10 the separating partitions 130₂ and 131₂ extend parallel to the side wall 3 to a median point along the unit and thence incline inwardly and forwardly toward the side wall 3, but stop short thereof and of the member 147. The outer side or separating partition 132₂ is also disposed parallel to the inner separating partitions. The arrangement of separating and side partitions shown in Fig. 10 is substantially the same as that shown in Fig. 5 of my copending application Ser. No. 574,033 now Patent No. 1,787,340.

In the operation of the mechanism, as the intermixed materials are fed downwardly and forwardly through the port 30, they are stratified and separated by the combined action of the vibration and the upwardly-directed air current, the heavier material sinking to the bottom and the lighter material rising to the top. Also, due to these agencies or forces, and to the inclination of the unit, the materials also travel forwardly and transversely outwardly with respect to the unit.

The separating partitions 130, 131 and 132 restrain any transverse movement of the bottom or heavier layer, and forces it forwardly along the bottom or table 1, whereas the lighter superior stratum suspended by the air currents, passes over the tops of the separating partitions 130, 131 and 132, and is discharged sidewise from the unit. Where the particles of material vary greatly in size, the plurality of separating partitions act to create a reseparation at each successive partition, so that the ultimate separation is practically complete.

The larger particles of the heavier material will immediately sink to the bottom of the stratum and will travel forwardly along the unit, upon the bottom 1, within the inner separating partition or wall. If smaller particles of the heavier material are impelled temporarily upwardly so as to pass over the first separating partition or wall 130, they will then sink to the bottom of the stratum within the next separating partition or wall 131, by reason of the relatively weaker air current, and will be impelled and restrained thereby to pass along the bottom 1 to the front end of the unit and will there be discharged with the remainder of the heavier material. The relatively weaker air current referred to may be provided by air current controlling or grading means such as the variations in deck perviousness disclosed in my application Serial No. 574,033 filed as of even date herewith (Patent No. 1,787,340). On the other hand, the upwardly directed air current and the transverse inclination and the vibration of the unit will impel the lighter material over the top of the separating partition.

The same conditions will obtain with respect to the next separating partition or wall, except that there is likely to be none or very little of the heavier material passing into the space inside this partition, as any proportion of small particles of the heavier material grows less and less between each pair of separating partitions or walls outwardly.

This construction is especially useful in the separation of intermingled divided coal, rock and "bone" or "bony" (a well-known substance which

is combustible but has a high ash content and low heat efficiency). The specific gravity of the so-called "bone" is greater than that of the coal, but less than that of the rock, and it will be discharged at a place between the discharge places or points of the coal and rock.

If desired, guiding plates or a deflector device may be provided to assist in the discharge of the superior lighter layer, and as embodied, each unit 10 is provided with a plate 136, arranged diagonally and transversely thereof, that is, inclined from the inner wall forwardly and outwardly to the outer wall of the unit. This plate 136 is likewise shown adjustable both along the unit and as to its horizontal inclination with respect to the unit. For this purpose, the plate 136 is shown having at its inner end and bottom edge a horizontally-disposed forwardly-projecting flange 137, having a bolt and slot connection 138 with a plate 139 20 mounted on and projecting from the side of the unit. It has a similar plate 140 having a bolt and slot connection 141 with the side plate 61.

Means are provided for creating an upward and backward air pressure at the forward or discharge end of the units, to effect the final separation of any remnant of the intermixed materials, such as the rock and "bony", which have not been separated by the previous devices and action. As embodied, a plate 146 is disposed over 30 the bottom 1 and extends across between the side walls of the unit, and at its rear end there is fixed or connected thereto an upwardly-extending plate 147, likewise extending across the unit. At either side of plates 146 and 147, and connecting 35 them together, are brackets 148, having a bolt and slot connection 149 with upwardly-extending standards 155 fixed on the plate 61. This gives a vertical regulation of the size of the passage beneath the plate 46.

40 In conjunction therewith, there may be employed, if desired an inclined gate 151, which closes the forward or discharge end of the bed of heavier material, but which is openable by the pressure exerted thereon from within the unit. The inclined gate will remain closed and will 45 function as described in any inclined position of the unit. This gate 151 is pivotally supported by hinges 152 from a horizontally disposed rod 153, carried by the uprights 150. The gate may be 50 weighted, if desired, and for this purpose is provided with a pin 154, fixed thereto and projecting from the outward side thereof, whereon weights may be hung.

55 In the separating action, the coal or other lighter material is stratified at the top and is discharged sidewise over the side walls, chutes 160 being attached to the units at either side thereof, these chutes being forwardly and downwardly inclined to receive and to discharge the coal. The 60 "bone" or "bony" will also be discharged over the side of the unit but toward the forward end thereof, and chutes 161 are preferably provided to receive and convey it away. Baffles or deflectors 162 may be employed at the point of separation between the coal and the "bone" to direct each into its proper chute. Similar baffles 65 163 may be employed at the forward end of the unit to direct the "bone" into the chute. The units are provided at their forward ends with chutes 164 through which the rock is conveyed 70 away.

75 The invention in its broader aspects is not limited to the specific mechanisms shown and described but departures may be made therefrom within the scope of the accompanying claims

without departing from the principles of the invention and without sacrificing its chief advantages.

What I claim is:—

1. A mechanism for separating intermixed divided materials, comprising a feed hopper having air pervious sides, and means for blowing air upwardly through the hopper and outwardly through said air pervious sides for blowing away dust from the intermixed materials. 10

2. A mechanism for separating intermixed divided materials, comprising a feed hopper having air pervious sides, means for blowing air upwardly through the hopper and outwardly through said air pervious sides for blowing away dust from 15 the intermixed materials, and means for regulating the amount of air thus supplied to the hopper.

3. A mechanism for separating intermixed divided material including in combination a vibratable frame, a pair of air-pervious separating decks carried thereby, said decks having transverse inclination in opposite sense with respect to a longitudinal center line, and said transverse inclinations being uniform throughout the length 20 of said decks along lines parallel to said center line, means for varying the transverse inclinations of the decks with respect to said center line, a common air chamber for supplying air under pressure to both of said decks, means for vibrating 25 the frame, and means for separately discharging superposed lighter and settled heavier materials. 30

4. A mechanism for separating intermixed divided material including in combination a vibratable frame, a pair of air-pervious separating decks carried thereby, said decks having transverse inclinations in opposite sense with respect to a longitudinal center line, and said transverse inclinations being uniform throughout the length 35 of said decks along lines parallel to said center line, means for independently varying the transverse slope of either deck, a common air chamber for supplying air under pressure to both of said decks, means for vibrating the frame, and means for separately discharging superposed lighter and 40 settled heavier materials. 45

5. A mechanism for separating intermixed divided materials including in combination a transversely-inclined, air-pervious deck, means for feeding said materials to the rear end of the deck, means for longitudinally reciprocating the deck, a substantially straight material-retaining wall disposed longitudinally of the deck along the upper side edge thereof, a plurality of side by side 50 separating partitions disposed transversely to the longitudinal axis of the deck, a material-retaining wall extending from the rear end of the table 55 forwardly along the lower side thereof for a shorter distance than said first mentioned retaining wall, the separating partitions beginning adjacent said lower retaining wall and extending forwardly and upwardly toward the upper retaining wall but having their forward ends terminating short thereof, and a spillage edge for lighter material disposed transversely of the table in the same direction as the separating partitions and extending from the front end of the lower retaining wall to beyond the front ends of the separating 60 partitions. 65

6. A mechanism for purifying coal having wide size variations, including in combination a transversely-inclined air-pervious deck, means for feeding said coal to the rear end of the deck, means for longitudinally reciprocating the deck, means 70 75

- for passing lifting and loosening air currents through substantially all parts of said deck, a plurality of substantially parallel separating partitions extending across the deck from the lower 5 toward the upper side thereof, a substantially straight material-retaining wall extending longitudinally along the upper side edge of the deck beyond the separating partitions, and a spillage edge for lighter material extending transversely 10 of the deck in the same direction as the separating partitions from a median point on the lower side of the deck to the front end thereof.
7. A mechanism for purifying coal having wide size variations, including in combination a transversely-inclined air-pervious deck, means for feeding said coal to the rear end of the deck, means 15 for longitudinally reciprocating the deck, means for passing lifting and loosening air currents through substantially all parts of said deck, a plurality of substantially parallel separating partitions 20 extending across the deck from the lower toward the upper side thereof, a substantially straight material-retaining wall extending longitudinally along the upper side edge of the deck 25 beyond the separating partitions, a spillage edge for lighter material extending forwardly and transversely of the deck from a median point on the lower side of the deck, and means for varying the transverse slope of the deck.
30. 8. A mechanism for separating intermixed divided materials of different specific gravities, including in combination a table having an air-pervious transversely inclined bottom, a bed-retaining wall along the upper side edge of said bottom, a forwardly and inwardly inclined spillage 35 edge for the lighter material opposite said bed retaining wall, said table being longitudinally reciprocable in a direction substantially parallel to said retaining wall and separating devices on said bottom for directing settled heavier material forwardly and upwardly toward the bed-retaining wall.
40. 9. A mechanism for separating intermixed divided materials of different specific gravities including in combination a table having a transversely inclined air-pervious bottom, a bed-retaining wall along one side edge thereof, the air-pervious bottom narrowing forwardly toward said bed-retaining wall, and separating partitions on 45 said bottom inclined forwardly and toward said bed-retaining wall, and means for reciprocating the bottom substantially in line with the bed-retaining wall and across the direction of the separating partitions.
50. 10. A mechanism for separating intermixed divided materials of different specific gravities, including in combination a table having an air-pervious bottom, means for longitudinally reciprocating the table, a bed-retaining wall along one side of said bottom for substantially its entire 55 length, a forwardly and inwardly inclined spillage edge extending forwardly from a point near the rear end of the table and terminating near the front end of the table, separating partitions on 60 said air-pervious bottom inclined forwardly and toward said bed-retaining wall, there being an unobstructed passage way along and adjacent to said bed-retaining wall for the passage of a settled heavier material and means for varying the transverse inclination of the table.
65. 11. A mechanism for separating intermixed divided materials of different specific gravities, including in combination a table having an air-pervious bottom, means for longitudinally reciprocating the table, a bed-retaining wall along one 70 side of said bottom inclined forwardly and from the lower side toward the upper side of the table, and means for varying 75
- side of said bottom, a relatively short opposite bed-retaining wall at the rear of said bottom, separating partitions on said air-pervious bottom inclined forwardly and toward said bed-retaining wall, a forwardly and inwardly inclined spillage edge extending forwardly from a point near the rear end of the table and terminating beyond the front ends of the separating partitions, there being an unobstructed passage way along and adjacent to said bed-retaining wall for the passage of a settled heavier material. 10
12. A process of separating intermixed divided materials which comprises maintaining a forwardly traveling and forwardly narrowing bed of the materials to be separated, the bed being pre-determinately inclined transversely according to the characteristics of the material, forcing lifting and loosening air currents through the bed, longitudinally reciprocating the bed, directing a settled heavy material toward the upper side of the bed and forwardly along that side in an unbroken concentrating stream, and discharging a superior stratum of lighter material from the opposite side of the gradually narrowing bed. 15
13. A mechanism for separating intermixed divided materials of different specific gravities including in combination a table having a transversely inclined air-pervious bottom, a bed-retaining wall along the upper side edge thereof, the air-pervious bottom narrowing forwardly and having a spillage edge for lighter material opposite said bed-retaining wall, separating partitions on said bottom inclined forwardly and transversely toward said bed-retaining wall, an unobstructed passage way for settled heavier material along the bed-retaining wall and above the separating partitions, means for longitudinally reciprocating the table, and means at the rear of the table for feeding the intermixed materials only to said unobstructed passage way. 25
14. A mechanism for separating intermixed, divided materials varying relatively very greatly in size and varying relatively little in their specific gravities, which comprises an air pervious table inclined upwardly both forwardly and transversely, means for supplying and maintaining upon the table a bed of materials undergoing separation, means for longitudinally reciprocating the table and means for effecting separation of the materials comprising devices for impelling the settled heavier material transversely of the table. 40
15. A mechanism for separating intermixed, divided materials varying relatively very greatly in size and varying relatively little in their specific gravities, which comprises an air pervious table inclined upwardly both forwardly and transversely, means for supplying and maintaining upon the table a bed of materials undergoing separation, means for longitudinally reciprocating the table and means for effecting separation of the materials comprising devices for impelling the settled heavier material transversely and from the lower to the upper side. 55
16. A mechanism for separating intermixed, divided materials varying relatively very greatly in size and varying relatively little in their specific gravities, which comprises an air pervious table inclined upwardly both forwardly and transversely, means for longitudinally reciprocating the table means for supplying and maintaining upon the table a bed of materials undergoing separation, means for effecting separation of the materials comprising separating partitions inclined forwardly and from the lower side toward the upper side of the table, and means for varying 70

both the lateral and the longitudinal inclinations of the table.

17. A mechanism for separating intermixed, divided materials varying relatively very greatly in size and varying relatively little in their specific gravities, which comprises an air pervious table inclined both lengthwise and transversely and narrowing forwardly from the feed toward the discharge end, means for supplying and maintaining upon the table a bed of materials undergoing separation, means for effecting separation of the materials comprising devices for impelling the settled heavier material transversely of the table, and a longitudinally disposed channelway to conduct the settled heavier material forwardly along the side edge of the table by friction and inertia, said channelway being unobstructed, whereby the heavier material may flow unrestrainedly therealong.

18. A mechanism for separating intermixed, divided materials varying relatively very greatly in size and varying relatively little in their specific gravities, which comprises an air pervious table inclined both lengthwise and transversely, means for supplying and maintaining upon the table a bed of materials undergoing separation, means for effecting separation of the materials comprising devices for impelling the settled heavier material transversely and from the lower to the upper side, and a longitudinally disposed channelway to conduct the settled heavier material forwardly along the upper side edge of the table by friction and inertia, said channelway being unobstructed, whereby the heavier material may flow unrestrainedly therealong.

19. The process of purifying coal which comprises maintaining a relatively long, narrow and transversely inclined bed of coal, progressing the bed forwardly by longitudinal reciprocation while forwardly narrowing said bed, passing lifting and loosening air currents through substantially all parts of the bed, directing a settled heavier material transversely toward the upper side of the bed and forwardly therealong in a concentrating stream discharging said concentrated stream, and progressing the superior stratum of lighter material downwardly and away from said stream and gradually discharging said lighter material along the lower side of the gradually narrowing bed.

20. A mechanism for separating intermixed divided materials of different specific gravities including in combination a transversely and longitudinally inclined bottom which is air-pervious in substantially all its parts, means for feeding the intermixed materials to the rear end of said bottom, a plurality of separating partitions disposed forwardly and toward the upper side of the bottom, means for preventing spillage of heavy material over the upper side edge of the bottom comprising a retaining wall extending along said edge, an unobstructed passageway for heavier material extending along said retaining wall and beyond the separating partitions, the

table being reciprocable substantially parallel to said wall and passageway, a spillage edge for lighter material extending forwardly and toward the retaining wall along the lower side edge of the bottom, and means for varying the transverse inclination of the bottom.

5

21. A mechanism for separating intermixed divided materials including in combination a pair of air-pervious separating decks, means for horizontally vibrating the decks, the decks extending side-by-side in the direction of said horizontal vibration, a common source of air under pressure for the two decks and means for passing air currents from said source upwardly through the decks, and means for variably inclining the decks 10 in opposite senses transversely to the direction of said vibration.

10

22. A mechanism for separating intermixed divided materials including in combination a pair of similar, relatively long and narrow air-pervious decks, means for longitudinally vibrating the decks together, said decks extending side-by-side in the direction of horizontal vibration and inclined in opposite senses transversely to said vibration, means for passing lifting and loosening 20 air currents through the decks, and means for independently varying the transverse inclination of either deck.

20

23. A mechanism for separating intermixed divided materials which comprises an air-pervious table inclined both lengthwise and transversely, means for feeding intermixed materials to a bed thereof undergoing separation upon the table, means for effecting separation of the materials comprising devices for impelling the settled 30 heavier materials transversely of the table, a longitudinally disposed channelway for conducting the settled heavier material forwardly along the side edge of the table by friction and inertia, said channelway being unobstructed, whereby the heavier material may flow unrestrainedly therealong, and a spillage edge for lighter material opposite the unobstructed channelway and extending forwardly and at an angle to said channelway.

30

24. A mechanism for separating intermixed divided materials which comprises a forwardly narrowing, air-pervious table inclined upwardly both forwardly and transversely, means for feeding intermixed materials to a bed thereof undergoing separation upon the table, means for effecting separation of the materials comprising separating partitions inclined forwardly and toward the upper side edge of the table for impelling settled heavier material transversely and from the lower toward the upper side, a longitudinally disposed channelway for conducting the settled heavier material forwardly along the upper side edge of the table by friction and inertia, said channelway being unobstructed, whereby the heavier material may flow unrestrainedly therealong, and a spillage edge for lighter material along the lower side edge of the table.
